(57) CLAIM

The ornamental design for a shelf for showcase as shown and described.

DESCRIPTION

FIG. 1 is a perspective view of a shelf for showcase of my design;

FIG. 2 is a front view thereof;

FIG. 3 is a rear view thereof;

FIG. 4 is a top plan view thereof;

FIG. 5 is a bottom plan thereof;

FIG. 6 is a left-side view thereof; and,

FIG. 7 is a right-side view thereof.

The broken lines illustrate structure or features which form no part of the claimed design.
